UNITED STATES PATENT OFFICE

WILLIAM A. TRAVER, OF PROVIDENCE, AND JOHN M. WOOD, OF PAWTUCKET, RHODE ISLAND, ASSIGNORS TO FRANKLIN PROCESS COMPANY, OF PROVIDENCE, RHODE ISLAND, A CORPORATION OF RHODE ISLAND

DYEING MACHINE

Application filed July 27, 1929. Serial No. 381,505.

This invention relates to improvements in apparatus for dyeing, bleaching, washing and otherwise processing fibrous materials, and particularly to machines for dyeing or otherwise treating raw stock such as wool, worsted, mohair and similar fibers.

One object of the invention is to provide a machine of the type specified wherein the material may be handled more conveniently and expeditiously in loading and unloading the kier or other vessel in which the fibers are dyed or treated.

Another object of the invention is to provide a machine of the type specified which is more efficient in use and generally more convenient to operate.

Another object of the invention is to provide a machine having a holder or carrier for the material to be treated embodying a central vertical standpipe around which the material is packed and having means to separate the mass into sections so that it may be easily removed from the carrier without clinging or binding thereon after treatment.

Another object of the invention is to provide means for automatically sealing the joint between the standpipe of the carrier and the intake-pipe of the kier or vessel in which the material is treated under the hydraulic pressure of the circulating system.

Further objects of the improvement are set forth in the following specification which describes one form of construction of the invention by way of example as illustrated by the accompanying drawings. In the drawings:

Fig. 1 is a vertical sectional view of a cylindrical kier or dyeing-vessel showing the present invention as embodied therein;

Fig. 2 is a sectional plan view of the same taken on line 2—2 of Fig. 1;

Fig. 3 is a perspective view illustrating the holder or carrier for the material to be treated in the machine; and

Fig. 4 is an enlarged sectional detailed view showing the means for connecting the standpipe of the carrier with the intake pipe of the kier.

In general, the invention consists in a dyeing-vessel or kier of any suitable form hav-

ing inlet and exhaust pipes for circulating the dye liquor or other fluid through the material to be treated and provided with an interior holder or carrier for supporting the material in the kier in a mass surrounding a perforated standpipe, with the carrier adapted to be lifted out from the kier to remove the material therefrom. A particular feature of the invention consists in means for automatically connecting the standpipe of the carrier with the intake pipe of the kier to secure a fluid-tight joint therebetween; and a further feature comprises means for dividing the mass of material surrounding the standpipe in two or more separate sections whereby it may be readily removed from the holder or carrier after the latter has been withdrawn from the kier.

The present invention may be applied to practically any type of dyeing-vessel, but as herein illustrated it is adapted for use with a cylindrical kier or vat such as shown in the drawings and designated generally by the reference character 2. The present form of kier is usually constructed with a circular wooden base or bottom 3 surrounded by vertical staves 4 which are bound together by means of suitable wire hoops 5. Abutting the lower ends of the staves 4 is a flat ring or annulus 6 which serves as the anchoring means for a series of vertical tie-rods 7. Surrounding the upper portion of the kier is a metal band or hoop 10 bolted to the staves 4 at 11. The vertical tie-rods 7 are inserted through holes 12 in the lower annulus 6 and secured thereto by units 13 with their upper ends screwed into threaded holes in the band or hoop 10.

A cover 15 seats across the top of the kier 2 with a gasket 16 arranged therebetween to provide a fluid-tight joint. The cover 15 is clamped down against the top of the kier by means of bolts 17 pivoted to ears 18 on the hoop or band 10. The bolts 17 are swung on their pivots to engage them with slots in the edge of the cover 15 and suitable nuts and washers, indicated at 19, are applied to their ends to clamp the cover down against the top of the kier. A reinforcing frame 20 of angle-irons braces the top of the cover 100

15 with the flanges of the latter slotted to receive the clamping bolts 17. The cover 15 is further braced by truss-rods 21 extending radially from the angle-irons of the frame 5 20 to a central support 22 constructed with a vertical tubular stem 23. A bolt 24 extends through the top of the stem 23 and carries a shackle-eye 25 which is employed in placing the cover on and lifting it off from the kier 10 by means of a suitable tackle or chain-hoist hooked thereto.

Fastened to the underside of the cover 15 is a framework 26 comprising a series of blocks 27 supporting a plurality of horizontal cross-bars or slats 28. The framework 26 projects down into the kier to adapt the slats 28 to bear against a suitable compression-plate or screen-grid 30 to force the latter down against the mass of material, represented at F in Fig. 1, in the manner and for the purpose as later more fully explained. The cover 15 may be provided with the usual testing instruments and appurtenances such as a pressure-gauge 31, thermometer 32 and a hand-hole cover 33 for sampling the batch as it is dried or treated in the kier. These parts of the apparatus are not essential to the present invention, however, and are therefore not described in detail.

30 As shown in Fig. 1, the kier 2 is preferably supported in raised position above the floor by means of a foundation of cement blocks or the like as indicated at 34. Opening through the center of the bottom of the kier is an intake-pipe 35 having its flange bolted to an annular plate 36 resting on the floor of the kier and formed with a raised seat-ring 37, see Fig. 4. An exhaust-pipe 38 leads from an opening 39 at one side of the inlet opening 40, being secured in place by bolts 41 anchored in a ring 42 let into the floor of the kier. The intake or feed-pipe 35 leads from a suitable pump connected with an expansion-tank and the exhaust-pipe 38 leads back to the tank with suitable valves for regulating the flow of the liquid to and from the kier, the arrangement of these parts being as usually employed and therefore not herein illustrated.

On the floor of the kier 2 is a circular rail 50 or ring 43 disposed adjacent the staves 4 and adapted to support a spider 44 constituting the bottom of the holder or carrier for the material which is indicated generally at 45. Referring more particularly to Figs. 1 and 55 2, a pair of vertical angle-irons 46 are arranged in diametrically opposite relation on the interior of the barrel of the kier, being fastened to its sides by means of screws 47. The angle-irons 46 serve as tracks for guiding 60 the carrier 45 into and out from the interior of the kier in the manner as later more fully explained.

The material holder or carrier 45, shown in perspective view in Fig. 3, comprises the lower spider 44 which is preferably con-

structed with a central hub 50 and radial arms 51 connected at their outer ends by a circular rib 52, see Fig. 2. The hub 50 of the spider or grid 44 has an axial hole in which is seated a vertical standpipe 55 having perforations 56 in its sides for the passage of the dye liquor or other fluid. Referring to Fig. 1, the standpipe 55 is held in place in the bore of the hub 50 by means of a ring 57 screwed onto its lower end and fastened in a counterbore 70 in the hub by means of screws 58. In the underside of the hub 50 is an annular groove forming a seat for a gasket or washer 60 which rests against the raised seat-ring 37 on the plate 36 fastened to the floor of the kier. The hydraulic pressure of the fluid against the material supported on the holder or carrier 45 causes the gasket 60 to be compressed between the hub 50 and the seat-ring 37 to effect a fluid-tight joint at this point in the manner as later explained. It will be understood that the liquid flowing into the kier from the intake-pipe 35 is forced upwardly through the standpipe 55 to flow into the upper part of the kier as a portion of it escapes through the perforations 56 in the pipe. The outer ends of the arms or ribs 51 of the spider 44 rest on the rail or ring 43 to support the main weight of the carrier 45 and the material contained thereon.

95 Resting across the top of the spider 44 is a perforated plate 61 which is preferably secured in place by screws or rivets 62 fastened in holes in the arms 51, see Fig. 2. The plate 61 is provided with slots 63 in its periphery to adapt it to slide down on the vertical angle-irons or guiding-tracks 46.

As shown most clearly in Fig. 3, the material carrier 45 is provided with a vertical plate 65 which divides its bottom plate 61 into two halves and extends nearly to the top of the standpipe 55. The plate 65 serves as a separator for dividing the mass of material carried on the carrier into two sections and, if desired, further radial plates may be employed to separate the mass into small segments. As herein illustrated, the separator-plate 65 comprises two portions extending diametrically of the standpipe 55 and fastened thereto by means of semi-circular clamps 66 riveted to the plate and the pipe. The separator-plate 65 is also fastened to the bottom plate 61 by means of angle-shaped gussets or clamps 67 riveted thereto. At the top of the standpipe 55 is a cross-bolt 68 to which is attached a shackle-eye 70.

The screen-grid or compression-plate 30 which is placed on top of the mass of material held on the carrier 45 is preferably formed in two halves as shown in Fig. 2. The screen-grid may comprise two sections, each having a framework 71 formed from a metal rod bent to conform to one-half of the interior of the kier and extending diametrically there-across with its center bowed outwardly at 73 125

to encircle the standpipe 55. Stretched across the framework 71 is a screen 74 of relatively heavy wire mesh. A suitable hand-hole 75 bound with a ring 76 is made in one of the sections of the screen-grid 30 to adapt it to register with the hand-hole through the cover 15 as shown in Fig. 1.

Having now described the construction and arrangement of the improved apparatus in detail, its method of operation will next be explained. With the cover 15 removed from the kier and the carrier or holder 45 in place therewithin the fibrous material is dumped onto the lower plate 61 and packed closely around the stand-pipe 55 clear to the top of the latter. The weight of the material and the carrier holds the hub of the carrier down on the seat-ring 37 and the outer ends of the arms 51 rest on the rail 43 to support the load. After the material has been packed into the kier in this manner the screen-grid 30 is set on top of the mass by placing its two halves in position as shown in Fig. 2. The cover 15 is then lowered into place and clamped against the top of the kier by means of the bolts 17 and nuts 19. As the cover is clamped down into place the slats 28 on its underside will bear against the rim of the screen-grid 30 to force the latter down against the material to compress it into a relatively dense mass and the batch is then ready for treatment with the dye liquor or other fluid.

The pump is started and the valves manipulated to cause the fluid to flow through the intake-pipe 35 and inlet 40 up into the standpipe 55, from which it is forced radially outwardly through the perforations 56 to penetrate the mass surrounding the standpipe.

It is to be particularly noted that the standpipe 55 is open at the top and that therefore the fluid will flow therefrom into the upper part of the kier where it creates hydraulic pressure against the mass of material on the carrier 45. This pressure is exerted against the carrier to force the hub 50 of the spider 44 down toward the bottom of the kier to compress the gasket 60 against the seat-ring 37, whereby to seal the joint at the intake-pipe 35. In this way the standpipe 55 is automatically connected to the intake-pipe 35 with a fluid-tight joint so as to obviate the necessity for manually coupling the parts together. The fluid circulated through the system permeates the mass both from the top and radially from its center, draining down through the perforated bottom plate 61 into the bottom of the kier, whence it is exhausted through the opening 39 and pipe 37 to return it to the expansion-tank. The material is treated in the manner as above explained for the required period and thorough permeation of the batch is secured so that the fibers may be dyed throughout with an even color. After the dying operation the batch may be washed

by circulating water through the kier in the same manner.

After the treating process is completed the cover 15 is lifted off from the top of the kier 2 and the screen-grid 30 removed from the top of the mass. A suitable tackle or chain-hoist is then hooked into the shackle-eye 70 and the holder or carrier 45 is hoisted out from the kier with the treated material contained thereon in a solid mass. After the carrier has been withdrawn from the kier the mass of treated material surrounding the standpipe 55 may be readily removed in two halves without the fibers clinging and binding around the pipe. The mass being separated into two halves, each section is easily drawn off from the bottom plate 61 and away from the standpipe 55 without the necessity of breaking it up or lifting the whole mass bodily upward. In this way considerable time and labor is saved and the mass of material is so divided as to be in more convenient form for transfer to further processes. Heretofore, where it has been necessary to lift the whole mass off from the bottom of the kier or from a carrier held therein, considerable difficulty has been experienced in separating it from the standpipe. With the present apparatus the mass of fibers is parted so that each half may be readily withdrawn and thereby the operation of removing the material from the kier is expedited and rendered more convenient.

While we have herein described and illustrated the invention as embodied in a preferred type of apparatus, it is to be understood that various modifications may be made in the construction and arrangement of the machine without departing from the spirit or scope of the invention. Therefore, without limiting ourselves to the precise construction shown and described, we claim:

1. In an apparatus for dyeing and otherwise treating fibrous materials, the combination of a closed vessel having an intake-opening in its bottom for admitting fluid under pressure, a removable carrier for holding the material within the vessel comprising a vertical standpipe open at its upper end and arranged with its lower end in communication with the intake-opening in the vessel, means for supporting the material packed around the standpipe, and a connection between the lower end of the standpipe and the intake-opening adapted to be sealed by the hydraulic pressure of the fluid flowing through the standpipe and acting against the top of the mass of material held on the carrier.

2. In an apparatus for dyeing and otherwise treating fibrous materials, the combination of a closed vessel having an intake-opening in its bottom for admitting fluid under pressure, a removable carrier for holding the material within the vessel comprising

a vertical standpipe open at its upper end and arranged with its lower end in communication with the intake-opening of the vessel, a bottom plate surrounding the standpipe to 5 adapt it to support the material, and a compression joint between the lower end of the standpipe and the intake-opening adapted to be sealed by the hydraulic pressure of the fluid flowing through the standpipe into the 10 top of the vessel and acting against the material on the carrier.

3. In an apparatus for dyeing and otherwise treating fibrous materials, the combination of a closed vessel having an intake-opening in its bottom for admitting fluid under pressure, a seat surrounding said opening, a carrier for the material to be treated comprising a bottom plate and a vertical standpipe open at its upper end and provided 20 with a seat at its lower end fitted to the seat of the intake, and a compression gasket arranged between said seats for sealing the joint between the standpipe and the intake under the hydraulic pressure of the fluid 25 flowing through the standpipe into the top of the vessel and acting against the mass of material on the carrier.

4. In an apparatus for dyeing and otherwise treating fibrous materials, the combination of a closed vessel having an intake-opening in its bottom surrounded by a seat, a removable carrier for holding the material within the vessel comprising a grid with a central vertical standpipe rising therefrom and open at its upper end with its lower end fitted to the seat surrounding the intake-opening, and compression means between the lower end of the standpipe and the seat of the intake for sealing the joint therebetween 40 under the hydraulic pressure of the fluid flowing through the standpipe and acting against the mass of material on the carrier.

5. In an apparatus for dyeing and otherwise treating fibrous materials, the combination of a closed vessel having an intake-opening in its bottom for admitting fluid under pressure, a seat-ring surrounding said intake-opening, a removable carrier for holding the material within the vessel comprising 50 a spider having a central hub adapted to seat against the seat-ring on the bottom of the vessel and a standpipe rising from said hub, and a gasket arranged between the hub and open at the top of the spider and the seat-ring 55 to seal the joint therebetween under the hydraulic pressure of the fluid flowing through the standpipe into the top of the carrier and acting against the mass of material held on the carrier.

6. In an apparatus for dyeing and otherwise treating fibrous materials, the combination of a kier, a removable cover for closing the top of the kier for admitting fluid under pressure, an intake in the bottom of the kier, 65 a seat surrounding the intake, a spider hav-

ing a central hub adapted to rest against the seat-ring, a gasket arranged between the hub of the spider and the seat on the bottom of the kier, a standpipe rising from the hub of the spider and open at the top, and a perforated plate resting on the spider to adapt it to support the material packed around the standpipe.

7. In an apparatus for dyeing and otherwise treating fibrous materials, the combination of a kier having an intake in its bottom, a seat surrounding said intake, a cover for closing the top of the kier, a raised rail on the bottom of the kier, a spider having a hub adapted to rest against the seat of the intake and having its outer circumference supported from the raised rail on the bottom of the kier, a gasket between the hub of the spider and the seat, a standpipe rising from the center of the hub of the spider, and a plate 75 on the spider for supporting the material packed around the standpipe.

8. In an apparatus for dyeing and otherwise treating fibrous materials, the combination of a closed vessel, and a removable carrier for holding the material within the vessel comprising a bottom plate, a vertical standpipe rising from the center of the plate, and a division plate extending diametrically 90 of the standpipe across the bottom plate to separate the mass of material packed around the standpipe into sections to facilitate its removal from the carrier.

9. A carrier for supporting fibrous materials to adapt them to be dyed or otherwise treated comprising a bottom plate, a vertical standpipe rising from the plate, and a division plate extending diametrically from the standpipe across the bottom plate to adapt it to separate the material packed around the standpipe into sections to facilitate its removal from the carrier after the dyeing or other treatment.

10. A carrier for holding fibrous material to be dyed or otherwise treated comprising a vertical standpipe, a spider secured to the lower end of the standpipe, a perforated bottom plate resting on the spider, and a vertical plate extending radially from the standpipe across the bottom plate to divide the mass of material into sections to facilitate its removal from the carrier after the dyeing or other treatment.

11. In a carrier for holding fibrous material for subjection to dyeing and other processes in a kier or vessel, the combination of a spider having a central hub with a framework radiating therefrom, a vertical standpipe secured in said hub, a perforated plate resting on the framework of the spider, and a division plate extending diametrically from the standpipe across the bottom plate.

12. In a carrier for holding fibrous materials for dyeing or otherwise processing in a kier or vessel, the combination of a spider 130

provided with a central hub formed with a bore, a vertical standpipe held in the bore in the hub, a bottom plate supported on the spider, and a vertical division plate constructed in sections extending radially of the standpipe across the bottom plate.

In testimony whereof we hereunto affix our signatures.
